UNITED STATES PATENT OFFICE.

OLE SATERBAKKEN, OF DUNN, TENNESSEE.

REIN-HOLDER.

SPECIFICATION forming part of Letters Patent No. 701,399, dated June 3, 1902.

Application filed March 31, 1902. Serial No. 100,855. (No model.)

To all whom it may concern:

Be it known that I, OLE SATERBAKKEN, a citizen of the United States, residing at Dunn, in the county of Lawrence and State of Tennessee, have invented certain new and useful Improvements in Rein-Holders; and I do declare the following to be a full, clear, and exact description of the invention, such as will enable others skilled in the art to which it applies to make and use the same.

This invention relates to improvements in rein-holders.

The object of the invention is to provide a rein-holder of that character employing cam-jaws which shall be simple of construction, applicable to any form of dash of a vehicle-body, and capable of being readily and conveniently regulated to clamp and release the reins or lines.

With this and other objects in view the invention consists of certain novel features of construction, combination, and arrangement of parts, which will be hereinafter more fully described, and particularly pointed out in the appended claim.

In the accompanying drawings, Figure 1 is a front view of a rein-holder embodying my invention, showing in full lines and in broken lines the operation of the cam-jaws; and Fig. 2 is a rear view of the same, showing in full and broken lines the operation of the segments and spring.

Referring now more particularly to the drawings, the numeral 1 represents a supporting-plate which is adapted to be secured by screws or other suitable fastening devices to the dash of a vehicle. Arranged upon the front or outer side of this plate are cam locking-jaws 2 and 3, provided with serrated faces which engage and hold the lines or reins inserted between them. One of these jaws is provided with a finger-piece 4 for convenience in opening the two jaws to release the reins. The jaws 2 and 3 are pivotally mounted upon short shafts or pintles 5, journaled in the plate 1 and projecting upon the rear side thereof, and rigidly mounted upon the rear ends of these pintles or shafts are two segments 6 and 7, which move synchronously with the jaws and are adapted to be operated by a spring 8 to normally hold said jaws closed or in clamped position. The spring 8 consists

of a single piece of wire bent into the form of a loop, which incloses the segments, the main arm of the loop being secured by suitable fastenings 9 to the plate and the opposite ends of the spring fitted in sockets or recesses 10, formed in said segments. At the ends of the loop or at the points intermediate the said fastening devices and the free end of the spring 60 are coils 11, which impart to said free ends of the spring sufficient elasticity or resiliency to cause them to normally move the segments to the position shown in full lines in Fig. 2, whereby the jaws 2 and 3 are brought together 65 so as to clamp the reins or lines when placed between them. The free ends of the spring are also adapted to yield to allow the segments to move to the broken-line position shown in Fig. 2 to allow the jaws to open to 70 receive the lines.

In the operation of the device when it is desired to have the lines held firmly the finger-piece 4 is pressed downwardly to open the jaws against the tension of the spring, movement being imparted to the jaw 2 from the jaw 3 through the instrumentality of the two segments, whereupon the opposing faces of the jaws will be opened to admit of the insertion of the lines between them. The finger-piece 4 is then released, whereupon the free ends of the spring will force the two segments back to the full-line position shown in Fig. 1, whereby the jaws will be closed to tightly grip the lines. By employing cam-jaws of 85 the construction shown all liability of displacement of the lines is obviated, as the tighter the pull upon the lines the tighter will be the gripping action of the jaws.

From the foregoing description, taken in connection with the accompanying drawings, the construction, mode of operation, and advantages of the invention will be readily understood without requiring an extended explanation.

Various changes in the form, proportion, and details of construction may be made within the scope of the invention without departing from the spirit or sacrificing any of the advantages thereof.

Having thus described my invention, what I claim, and desire to secure by Letters Patent, is—

A rein-holder comprising a supporting-

plate, cam-jaws mounted upon one side of the plate, one of said jaws being provided with a finger-piece, shafts or pintles connected to the jaws and projecting through the plate, toothed segments connected to said shafts or pintles on the opposite sides of the plate, and a loop-wire spring secured to the plate and having its free ends connected to the segments and provided with spring-coils, the said free ends of the spring normally tending to force the

segments to a position in which the segments act to force the jaws closed, substantially as set forth.

In testimony whereof I have hereunto set my hand in presence of two subscribing witnesses. 15

OLE SATERBAKKEN.
